(57) **CLAIM**

The ornamental design for a bottle neck with nest indents, as shown and described.

DESCRIPTION

FIG. 1 is a bottom left isometric view of the present design a bottle neck with nest indents.

FIG. 2 is a top left isometric view of the present design shown in FIG. 1.

FIG. 3 is a left side plan view of the present design shown in FIG. 2.

FIG. 4 is a right side plan view of the present design shown in FIG. 2.

FIG. 5 is a bottom plan view of the present design a shown in FIG. 1.

FIG. 6 is a top plan view of the present design a shown in FIG. 2.

FIG. 7 is a partial enlarged view of the portion circled in FIG. 6.

FIG. 8 is a bottom left isometric view of an alternate embodiment of the present design a bottle neck with nest indents.

FIG. 9 is a top left isometric view of the present design shown FIG. 8.

FIG. 10 is a left side plan view of the present design shown FIG. 9.

FIG. 11 is a right side plan view of the present design shown FIG. 9.

FIG. 12 is a bottom plan view of the present design shown FIG. 8.

FIG. 13 is a top plan view of the present design shown FIG. 9.

FIG. 14 is a partial enlarged view of the portion circled in FIG. 13.

FIG. 15 is a bottom left isometric view of an alternate embodiment of the present design a bottle neck with nest indents.

FIG. 16 is a top left isometric view of the present design shown FIG. 15.

FIG. 17 is a left side plan view of the present design shown FIG. 15.

FIG. 18 is a right side plan view of the present design shown FIG. 16.

FIG. 19 is a bottom plan view of the present design shown FIG. 15.

FIG. 20 is a top plan view of the present design shown FIG. 16; and,

FIG. 21 is a partial enlarged view of the portion circled in FIG. 20.

In the drawings, the evenly-spaced broken lines show portions of a bottle neck with nest indents and form no part of
